To all whom it may concern:

Be it known that I, Charles E. Van Bibber, a citizen of the United States of America, residing at Phoenix, in the county of Mariposa and State of Arizona, have invented a new, original, and ornamental Design for a Transparent Rigid Top for Convertible Automotive Vehicles, of which the following is a specification, reference being had to the accompanying drawing, forming a part thereof.

Fig. 1 is a side elevational view of the transparent rigid top for convertible automotive vehicles, showing my new design.

Fig. 2 is a side perspective view of the same, and

Fig. 3 is a rear partially perspective view showing my new design.

In all figures the dot and dash line showing portions of a conventional motor vehicle body is for illustration purposes only.

I claim:

The ornamental design for a transparent rigid top for convertible automotive vehicles, substantially as shown and described.
